UNITED STATES PATENT OFFICE

ANTHONY BOEDEKER, OF CINCINNATI, AND JESSE S. WENTWORTH, OF NORWOOD, OHIO, ASSIGNORS TO GRANDTONE RADIO CORPORATION, OF CINCINNATI, OHIO, A CORPORATION OF OHIO.

RADIOCONDENSER.

Application filed March 7, 1925. Serial No. 13,770.

This condenser is particularly applicable and useful in connection with radio apparatus, although it may be used as a condenser in connection with any other apparatus or device, when found practicable for such use.

Our invention relates to a radio condenser, particularly of the variable type and has for its purpose the same functioning as the general type of radio variable condensers such as known to the trade or in the art.

The main feature of our condenser is its straight line relational functioning and would be better known to the trade as a radio variable straight line condenser, from the fact that the two opposite units or positive and negative sections of blade or vanes pass into correlation with each other (or vice versa) in a straight line without variation of position other than inward or outward direction, and thus presenting a minimum or maximum plate surface on each opposite unit as the case may require.

The advantage of the straight line condenser of our particular description, over the generally used condenser of today, is that there is no repetition of reception caused by the adjustment of the condenser as is found in the condenser of the rotatable type. The general adjusting control of our condenser may be along the lines of any well known mechanical construction such as is used for moving mechanical units in a fixed directional straight line, or in an inward or outward straight line, and yet holding one unit in correlation with the other, in a fixed or adjustable relation.

In our condenser a pair of units are employed as before set forth, each unit formed of spaced blades, the blades of one unit adapted to enter between the blades of the opposite unit, to a greater or less degree and adapted to move in straight lines parallel to the blades; one of the units may be stationary and the other movable or they may both be movable toward each other as is found best in practise and under the circumstances.

The various features and advantages of our invention will readily become apparent from a perusal of the following specification and claims.

In the accompanying drawing forming part of this specification:—

Fig. 1, is a plan view of our new straight line condenser.

Fig. 2, is a side elevation thereof, showing the adjustable feature in light dotted lines.

Fig. 3, is an end view of the condenser.

Fig. 4, is a side elevation, with parts broken away to illustrate construction of our condenser, showing the same with a double adjustment.

Fig. 5, is a view in elevation of one end of the condenser shown in Fig. 4, and

Fig. 6, is a view in elevation of the opposite end of the condenser shown in Fig. 4.

Our new condenser is made up of a base 1, having at its sides, the guides 2, into which is mounted the slide 3, carrying the supports 4.

Instead of using a base as 1, the condenser may be placed into any position, it may be placed vertically or at an angle and supported in such manner, or it may be suspended as occasion and circumstances may require.

Mounted at the top, in the supports 4, is a shaft or pin 5 and at the bottom we provide the shaft or pin 6. These pins carry the blades or vanes 7 suitably spaced by the spacers or separators 8, and mounted on the shafts or pins 5 and 6. This describes one unit of the condenser. This unit is adjustable back and forth by the adjusting lever 9 which is pivotally mounted on the pin 10 supported in the base 1. At the point 12, we pivotally mount one end of a link 13, the other end of which is pivotally mounted on the pin 6. As the lever 9 is drawn back and forth, the blades 7 are drawn in and out of correlation with the blades 14, which are part of the opposite unit. This unit is composed of said blades 14, which are supported on the pins 15 and 16, mounted in the stationary supports 17, of the base 1. Spacers or separators 18 suitably space the blades 14 to work in correlation with the blades 7 and the separators 18 are on the pins or shafts 15 and 16.

A terminal 19 is provided by the nut connection on the pin 15, to supply current to one unit, the other terminal 20 formed by

the nut connection on the pin 5 imparts current to the blades 7 of the opposite unit.

In Figs. 4, 5, and 6, we show the double adjustment in which case both units are adjustable. This adjustment is accomplished as follows: The supports 21 are carried on a slide 22 which is mounted in the base 1, in the present instance having guides 2. In order to adjust the unit formed by the blades 14, we provide the lever 23 mounted on pin 24, secured in base 1. At a point 25 we mount one end of an arm 26, the other end of which is pivotally mounted in the support 21; by drawing back and forth on the handle or lever 23, the blades 14 can be adjusted back and forth.

The inward and outward action of the correlated parts regulates the volume capacity of electric current of condenser. Any operating means may be used instead of the handle lever.

We have described our preferred form and construction, but may deviate therefrom and modify the same so long as said construction and modification falls within the scope of the present specification and claims.

What we claim as new and our invention and desire to secure by Letters Patent is:—

30 1. In a condenser, a base, plate carrying supports arranged in pairs upon said base and one of said pairs movable as a unit toward or away from the other pair, a lever

pivoted to said base, and a link connecting said lever with said movable pair of supports.

2. In a condenser, a base having grooves therein, a pair of supports relatively fixed to said base, a slide arranged for travel in said grooves toward or away from said supports, a pair of supports affixed to said slide, spaced plates carried by each of said pairs of supports and capable of travel in the spaces between each other, a lever on said base, and a link connecting said lever with said slide carried supports.

3. In a condenser, a base having spaced pairs of grooves therein parallel to each other, slides having their ends engaged in said grooves and capable of moving toward or away from each other, supports arranged in spaced relation and extending outwardly from said slides, condenser plates arranged in spaced relation and carried by each of said pairs of supports and capable of moving longitudinally of each other into the spaces between the plates of the respective supports, a lever pivoted at each end of said base, and a link connecting each lever with a post of the next adjacent pair.

In testimony whereof, we affix our signatures at Cincinnati, Ohio, this 4th day of March, 1925.

ANTHONY BOEDEKER.
JESSE S. WENTWORTH.
